CLAIM

The ornamental design for a patch panel, as shown and described.

DESCRIPTION

FIG. 1 is a perspective view of a patch panel showing our new design;

FIG. 2 is a top plan view thereof;

FIG. 3 is a side elevational view thereof, the opposite side elevational view being a mirror image;

FIG. 4 is a front elevational view thereof;

FIG. 5 is a rear elevational view thereof;

FIG. 6 is a perspective view of a patch panel showing a second embodiment of our new design;

FIG. 7 is a top plan view thereof;

FIG. 8 is a side elevational view thereof, the opposite side elevational view being a mirror image;

FIG. 9 is a front elevational view thereof;

FIG. 10 is a rear elevational view thereof;

FIG. 11 is a perspective view of a patch panel showing a third embodiment of our new design;

FIG. 12 is a top plan view thereof;

FIG. 13 is a side elevational view thereof, the opposite side elevational view being a mirror image;

FIG. 14 is a front elevational view thereof; and

FIG. 15 is a rear elevational view thereof.
